Primary Examiner — Terry A Wallace(74) *Attorney, Agent, or Firm* — McCormick, Paulding & Huber LLP(57) **CLAIM**

The ornamental design for a food product dispensing bottle, substantially as shown and described.

DESCRIPTION

FIG. 1 is a front, top, right-hand side perspective view of a food product dispensing bottle, comprising a new, original and ornamental design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the food product dispensing bottle and form no part of the claimed design.
